UNITED STATES PATENT OFFICE.

ANDREW OPSAL, OF VANCQUVER, BRITISH COLUMBIA, CANADA.

LOG-LOADING BOOM.

1,279,746.

Specification of Letters Patent. Patented Sept. 24, 1918.

Application filed June 29, 1918. Serial No. 242,575.

To all whom it may concern:

Be it known that I, ANDREW OPSAL, a citizen of the United States, residing at Vancouver in the province of British Columbia, Canada, have invented certain new and useful Improvements in Log-Loading Booms, of which the following is a specification.

This invention relates to an improvement in a log-loading boom such as is used for transferring logs from a log pile to a railway car or platform, and in the manner for rigging the same to enable the work to be done more expeditiously and more safely, both for the life and limb of the operators and for the rolling stock on which the logs are to be loaded.

The old system of swinging the logs from a single loading line is both awkward to accomplish in attaining the balance of the logs, and is dangerous because of the uncertainty of that balance and the difficulty of preventing the log from swinging on a single suspension line. They are now, therefore, commonly lifted by two lines connected to lift and lower together from a horizontally disposed boom, and, that the axis of the log when hanging from the boom may be adjusted to be parallel with the track on which is the car to be loaded the sheaves on the boom over which the two lifting lines pass are carried on offsets disposed across the boom. While this is a valuable improvement over the former system of single line loading, it imposes a heavy twist on the boom stick and its several connections to the spar pole.

Further: The separate lines by which the logs are lifted and are checked against spinning, are usually connected to one lifting line before passing over the sheave on the spar pole to the drum of the donkey engine, so that while the logs may be lifted within a limited range from a log pile and swung onto a car there is little range of movement of the line enabling a log to be dragged from any distance and lifted.

Instead of using a horizontally disposed single boom stick mounted to swing radially about its spar pole I provide two boom sticks secured together to be substantially parallel to one another. The outer ends of these boom sticks are maintained the required distance apart by two transverse cross members, and the inner ends are stepped into and secured to a pivot casting mounted on the spar pole to swing around

the same through any desired angle. On the transverse members of the boom the sheaves around which the lifting lines pass for connection to the load are adjustably secured at any desired position on each boom stick on opposite sides of the middle line between the two. The torsional moment imposed on the boom by the resultant of the lifting line pressure on opposite sides of the middle line is thus met by a wide base connection to the spar pole.

Again, the lifting lines which pass around these sheaves on the transverse members of the boom, instead of being connected to the single hauling line from the drum of the hauling engine, between the boom and the sheave on the spar pole, pass over separate and independent sheaves on opposite sides of the spar pole, and are connected to the single hauling line between the spar pole and the drum of the hauling engine, so that any desired range of haul of the logs to the boom may be provided for by moving the hauling engine out the required distance from the spar pole.

The means by which these ideas are practically carried out are fully set forth in the following specification, reference being made to the drawings by which it is accompanied, in which:

Figure 1 is a side elevation of the double boom.

Fig 2, a plan of the same.

Fig. 3, a cross section on the line 3—3 in Fig. 2, and

Fig. 4 is an elevation to a reduced scale showing the lines connecting the boom to the spar pole and donkey engine, and

Fig. 5 is a plan of the same.

In these drawings 2 represents the spar pole, for which purpose a standing tree, if available, is preferably selected. The boom, which, in conjunction with the spar pole, forms the principal feature of this invention, is constructed of two boom sticks 5 which are secured parallel to one another at the required distance apart in a horizontal plane by a distance member 3 at the end adjacent the spar pole. This member 3 is hollowed to roughly fit the cross section of the spar pole through approximately its half circumference and is retained in position thereon by a strap or chain 4.

Each end of this distance piece against which the boom sticks 5 are secured is hollowed to the approximate circle of the cross

section of the boom stick and has an end across the arc of the hollow to support the sticks against endwise movement. Toward the outer end the boom sticks 5 are maintained the required distance apart by transverse members 6 which are shaped, as shown in Fig. 3, to fit the underside of each boom stick 5 to which they are secured by bolts, and they have a downwardly projecting web 7 which is provided with a series of apertures 8 for connection of a shackle 9 to any one of them by which the guide sheaves 10 of the lifting lines are connected.

This boom 5 is suspended from the spar pole 2 in a substantially horizontal position by a line 11 connected from a fixed strap or clamp 12 secured to the spar pole a short distance above the boom to each boom stick on each side of the spar pole. The outer end 29 of the boom is carried by a line 15 from toward the upper end of the spar pole to the extreme outer end of each boom stick. The transverse members 6 are spaced apart such a distance as will effectually check swinging 25 of the log about a vertical axis and insure that each lifting rope will receive a fair proportion of the weight. For general purposes they will be about fourteen feet apart.

The lifting lines 16 by which the load is drawn from the log pile and lifted for transference to the loading platform or direct to a car on the track 20 are connected to the log 21 by slings or tongs and pass through sheaves 10 connected to the shackles 9 on each transverse member 6. The position of the shackles 9 on each side of the middle line of the boom 5 will be such as will normally suspend the log immediately over and parallel to the track, the different apertures 8 affording means for adjustment of this angle of normal suspension as required.

The lines 16 pass over separate sheaves 18, one on each side of the spar pole and thereafter are connected to the line 17 from the drum 13 of the hauling engine at a sufficient distance from the spar pole as to permit the required range of movement of the log lifting lines 16.

Further connections may require to be made to the boom to normally return it to the loading position over the car on the track 20, and for pulling the boom away from this normal position to the position from which the logs are to be lifted. Means may also be provided for counterweighting the lifting lines 16 to insure that they will fall through the sheaves 10 when required. These supplementary connections are not material to this application and need not therefore be illustrated or further described.

It will be noted that the manner of suspension of the inner or spar pole end of the boom imposes a normal tendency on it to be stable when the suspension lines 11 and 15 are straight between their connections to

spar pole and boom, and this condition should exist when the boom end is over the track.

The essential feature of the invention lies in the construction of the boom 5 with its two boom sticks held four or five feet apart by the member 3 which pivots on the spar pole 2, and at the other end by the transverse members 6, 7 to which the lifting line sheaves 10 are connected at any desired positions on opposite sides of the middle line between the two boom sticks: Also in the connection of the lifting lines 16 to the single line 17 from the drum 13 of the hauling engine, between that engine and the spar pole 80 to which features substantial advantages are attributable in a stronger and better working boom and a greater range.

Having now particularly described my invention, I hereby declare that what I claim as new and desire to be protected in by Letters Patent, is:

1. A log loading boom, comprising the combination with an upright spar pole, of a boom horizontally suspended therefrom to be susceptible of pivotal movement around the spar pole, said boom consisting of two boom sticks horizontally spaced apart by a distance piece at one end which is hollowed out to fit the spar pole and toward the other end by spaced apart transverse members, a sheave connected to each transverse member on opposite sides of the middle lines between the boom sticks through which sheaves divided lifting lines from the hauling engine 100 pass for connection to the log.

2. A log loading boom, comprising the combination with an upright spar pole, of a boom horizontally suspended therefrom and susceptible of pivotal movement around the spar pole, said boom consisting of two timbers horizontally spaced apart by a distance piece at one end which is hollowed out to fit the spar pole and toward the other end by transverse members secured to the undersides of the boom sticks, said transverse members having provision for connection of sheave blocks to them at variable distances on each side of the middle between the two boom timbers, and load lifting lines connected to a line from the drum of the hauling engine, said lines passing through a sheave on each side of the spar pole and around the sheave on the transverse members of the boom.

3. A log loading boom, comprising the combination with an upright spar pole, of a boom horizontally suspended therefrom to be susceptible of pivotal movement around the spar pole, said boom having transverse frames near the outer end with provision for connection of a sheave to each transverse frame on opposite sides of the middle line of the boom, and a load lifting line taking around each sheave on the transverse mem- 125

bers of the boom and around sheaves on the same sides of the spar pole the two lines being connected to a single line from the drum of the hauling engine between the spar pole 5 sheaves and the hauling engine reel.

4. A log loading boom, comprising the combination with an upright spar pole, of a boom horizontally suspended therefrom and susceptible of pivotal movement around 10 it, said boom consisting of timbers horizontally spaced apart on each side of the spar pole by a stance piece at one end which is hollowed to fit the spar pole and has provision for retaining it thereagainst and to- 15 ward the other end by transverse members

secured to the undersides of the boom timbers, sheave blocks connected to the transverse members on opposite sides of the middle line of the boom, the suspension of the boom from the spar pole being by short lines connected to each boom stick adjacent the spar pole and by lines from the upper end of the spar pole connected to the outer end of each boom stick, and log lifting lines connected to a line from the drum of the hauling engine and taking over sheaves on each side of the spar pole and around the sheave on each transverse member of the boom. 20 25

In testimony whereof I affix my signature.

ANDREW OPSAL.
